UNITED STATES PATENT OFFICE.

EDWARD L. HEITZ, OF ST. LOUIS, MISSOURI, ASSIGNOR OF ONE-TENTH TO FRANK W. EILERMANN, OF ONE-TENTH TO WILLIAM McGUIRE, AND ONE-TENTH TO ALBERT W. JAEGER, ALL OF ST. LOUIS, MISSOURI.

ROTARY INTERNAL-COMBUSTION ENGINE.

1,332,397.

Specification of Letters Patent.

Patented Mar. 2, 1920.

Application filed September 6, 1919. Serial No. 322,081.

To all whom it may concern:

Be it known that I, EDWARD L. HEITZ, a citizen of the United States, residing at St. Louis, Missouri, have invented a certain new and useful Improvement in Rotary Internal-Combustion Engines, of which the following is a full, clear, and exact description, such as will enable others skilled in the art to which it appertains to make and use the same, reference being had to the accompanying drawings, forming part of this specification.

My invention relates to new and useful improvements in internal combustion engines of the rotary type, the principal objects of my invention being to generally improve upon and simplify the construction of the existing forms of rotary internal combustion engines; to provide a relatively simple and efficient rotary engine that derives its power from the combustion and consequent expansion of combustible vapors, the power of such combustion being applied directly to the periphery of the rotor of the engine; to provide simple and efficient means operated directly from the engine shaft for compressing the combustible vapors in the ignition chambers of the engine; and, further, to provide a rotary engine which can be very economically operated and which engine, by virtue of its size and construction, can be advantageously employed wherever high speed rotary motion is desirable and particularly upon motor vehicles, motor boats, aeroplanes and the like.

With the foregoing and other objects in view, my invention consists in certain novel features of construction and arrangement of parts hereinafter more fully described and claimed, and illustrated in the accompanying drawings, in which—

Figure 1 is a side elevational view of a rotary internal combustion engine of my improved construction, parts thereof being broken away and in section.

Fig. 2 is a detail section taken approximately on the line 2—2 of Fig. 1.

Fig. 3 is an enlarged detail section showing the packing means employed between the rotor and the inner face of the wall of the housing of the engine.

Fig. 4 is a cross section taken approximately on the line 4—4 of Fig. 5.

Fig. 5 is a section taken approximately on the line 5—5 of Fig. 4.

Referring by numerals to the accompanying drawings which illustrate a practical embodiment of my invention, 10, 10 designate the side walls of the housing or casing of the engine, and 11 the peripheral wall thereof, the latter being provided with a chamber 12 for a circulating cooling medium such as water.

Formed in the peripheral wall 12 at diametrically disposed points thereupon are elongated combustion chambers 13, the same being tangentially disposed with respect to the inner periphery of the wall 11 and seated in the walls of these combustion chambers 13 are ordinary spark plugs 14. Formed through the wall 11 immediately adjacent to these combustion chambers 13 are exhaust openings 15.

Arranged for sliding movement in suitable guideways formed in the walls 10 and 11 near the forward portion of each combustion chamber 13 is a plate 16 which performs the functions of a valve in that it closes the forward end of the combustion chamber when the combustible gases are being compressed therein and said plate being withdrawn to permit the force of the exploded vapors to pass outwardly into the rotor chamber. Each of these plates is provided with a centrally arranged stem 17 that projects outwardly through a bearing formed in wall 11, the outer end of said stem being provided with a head 18, and there being an expansive coil spring 19 arranged on said stem beneath said head. The pressure normally exerted by this spring tends to move the plate 16 into open position.

Fulcrumed on the engine casing adjacent to each stem 17 is a short lever 20, the inner end thereof bearing against the head 18 of the corresponding stem and the outer end of each lever is engaged by a push rod 21, the latter being mounted for sliding movement in suitable bearings 22 that are formed on compression cylinders 23 and which latter are formed on or fixed to one of the side walls 10 of the engine casing adjacent to the combustion chambers 13.

The inner ends of the push rods 21 carry rollers 24 which latter bear directly against the peripheries of a cam 25 having high and low portions and which cam is fixed on a

crank shaft 26^a. This crank shaft 26^a has its inner end mounted in a bearing formed in one end of the engine shaft 26 and the outer end of said crank shaft is journaled in 5 a suitable bearing formed on a bracket 26^b that is fixed to and projects outwardly from the engine housing. Carried by the engine shaft 26 within the housing of the engine is a rotor 27 provided in its periphery with a 10 series of elongated pockets 28 each of which is provided at its forward end with a face 29 which is radially disposed with respect to the axis of the rotor.

Arranged for sliding movement in the 15 peripheral portion of the rotor and immediately adjacent to and parallel with the faces 29 at the forward ends of the pockets 28 are packing plates 30, the outer ends of which are adapted to bear against the inner 20 surface of the wall 11 of the engine casing.

Seated in the lower portions of packing plates 30 are rods 31 and bearing against the lower ends thereof are expansive coil springs such as 32. These springs tend to 25 normally maintain the outer ends of the plates 30 in close contact with the inner surfaces of the wall 11 of the engine casing, thereby providing an effective packing between the peripheral pockets 28 and by providing the rods 31 between said packing plates and the springs 32, the transmission 30 of heat to said springs is minimized, with the result that said springs will have longer life or longer periods of service than if they 35 were in direct contact with the packing plates 30.

Arranged for operation in the cylinders 23 are pistons 33 and the piston rods 34 that are associated with said pistons are connected to a crank 35 on the shaft 26^a. Fixed 40 on the outer end of the engine shaft 26 is a pinion A which meshes with a pinion B, the gear ratio between said pinions being two to one and said pinion B being fixed on shaft 45 C that is journaled in a suitable bracket D. The rotary motion of shaft C is transmitted to crank shaft 26^a by conjoined pinions 37, one of which is fixed on shaft D and the other on crank shaft 26^a. An electric spark 50 timing device 36 is supported in any suitable manner on the engine casing and is driven from shaft C by suitable beveled pinions E. This timing device receives current from a suitable source of supply, preferably 55 a storage battery 38 and leading from said timing device to the spark plugs 14 are conductors 39. A carburetor 40 of any desired construction is supported on the lower portion of the engine housing and leading 60 therefrom to chambers 41 at the outer ends of the compression cylinders 32 are combustible vapor supply pipes 42.

Formed through the walls of the cylinders between the chambers 41 and the compression chambers within said cylinders are

70 apertures 42 that are normally closed by spring-held inlet valves 43. Formed at the outer ends of the cylinders 23 adjacent to the pockets 41 are pockets 44, the same communicating directly with the combustion chambers 13 and formed through the walls that separate these pockets 44 from the compression chambers within the cylinders 23 are openings 45 that are normally closed by 75 spring-held outlet valves 46.

75 The operation of my improved engine is as follows:

Combustible vapor is drawn alternately 80 into the compression cylinders 23 upon the suction stroke of the pistons 33, such combustible vapor passing from carburetor 40 through pipes 42 into the pockets 41 and from thence through the openings 42 as the inlet valves 43 are drawn into open positions as a result of suction produced by said pistons 33.

On the opposite or compression strokes of 85 said pistons, the charges of combustible vapor drawn into the cylinders 23 will be partially compressed therein and the pressure thus produced will force valves 46 open and said charges will be forced into and compressed in the combustion chambers 13, it being understood that during this compressing of the combustible gases, the plates 90 16 at the forward ends of the combustion chambers are closed.

Immediately after the point of highest 95 compression of the combustible charges, the timing device 36 acts to produce a spark between the terminals of plug 14 thereby igniting the compressed charge and at the same time the roller 24 on the inner end of the corresponding push rod 21 rides onto the low portion of the corresponding cam, thereby permitting the spring 19 on the corresponding stem of the valve plate 16 to act to open said valve plate and the force of the explosion and the expansion of the combustible gases will escape from the combustion chamber and pass outwardly therefrom directly against the radially disposed faces 110 29 at the ends of pockets 28.

115 It is contemplated that the rotor of my improved engine will have a normal speed of several hundred revolutions per minute and consequently the peripheral speed of said rotor will be comparatively high.

The plate valve 16 will maintain its open 120 positions as long as the corresponding roller is on the low portion of the corresponding cam 25 and this open pressure of said valve permits all of the force of the explosion and the expansion of the exploded gases to be directed outwardly onto a number of the radial faces 29 at the ends of the pockets 28 and this impact or force will drive the rotor at relatively high speed and with considerable power.

125 Inasmuch as there are two compression 130

cylinders and two combustion chambers and the crank shaft 26^a is driven at twice the speed of the rotor, there will be four explosions of combustible charges for each complete revolution of the rotor, and consequently the power developed by the engine will be practically continuous. The burnt gases or products of combustion from the engine find exit through the exhaust openings 15.

An engine of my improved construction is comparatively simple in construction and operation, can be easily and cheaply manufactured, and is particularly effective whenever the economical production of high speed rotary motion is desired.

It will be readily understood that minor changes in the size, form and construction of the various parts of my improved engine may be made and substituted for those herein shown and described, without departing from the spirit of my invention, the scope of which is set forth in the appended claims.

25 I claim:

1. In an engine, a rotor provided in its periphery with pockets, each of which pockets is provided at one end with a tangentially disposed face, a housing for said rotor, there being elongated combustion chambers formed in said housing, which combustion chambers are tangentially disposed with respect to the periphery of the rotor, normally open spring-held valves arranged adjacent to the forward ends of said combustion chambers, means adapted to be actuated by the shaft of the rotor for closing said valves, cylinders adjacent to said combustion chambers, valves controlling communication between the chambers in said cylinders and said combustion chambers, and means including pistons operating in said cylinders and adapted to be actuated by the shaft of the rotor for compressing combustible gases in said combustion chambers.

2. In an engine of the class described, a rotor provided in its periphery with pockets, each of which is provided at one end with a radially disposed face, a housing for said rotor, said housing being provided with a pair of oppositely disposed combustion chambers, the forward ends of which communicate with the rotor chamber in the housing, normally open spring-held valves mounted adjacent to the forward ends of said combustion chambers for controlling the escape of combustible vapors from said combustion chambers, and there being exhaust openings formed in the engine housing adjacent to the rear ends of said combustion chambers.

3. In an engine of the class described, a housing, a shaft journaled therein, a rotor carried by said shaft, the periphery of which rotor is provided with a series of

pockets, each having a radially disposed face at one end, there being elongated combustion chambers formed in said housing, which combustion chambers are tangentially disposed with respect to the periphery 70 of the rotor, compression cylinders arranged on the engine housing, normally closed spring-held valves controlling the passage of compressed vapor from said compression cylinders to the combustion 75 chambers, means adapted to be actuated by the engine shaft for opening said valves, there being exhaust ports formed in the engine housing adjacent to the rear ends of the elongated combustion chambers, and 80 means adapted to be actuated by the engine shaft for compressing combustible vapor in said compression cylinders.

4. In an engine of the class described, a 85 housing, a shaft journaled therein, a rotor carried by said shaft and provided in its periphery with pockets each of which is provided with a radially disposed face at one end, there being an elongated combustion chamber formed in the annular wall of the 90 engine housing, which combustion chamber is tangentially disposed with respect to the periphery of the rotor, and a spring-pressed plate adapted to close the forward end of 95 said combustion chamber.

5. In an engine of the class described, a 100 housing, a shaft journaled therein, a rotor carried by said shaft and provided in its periphery with pockets each of which is provided with a radially disposed face at one end, there being an elongated combustion chamber formed in the annular wall of the engine housing, which combustion chamber is tangentially disposed with respect to the 105 periphery of the rotor, a spring-pressed plate adapted to close the forward end of said combustion chamber, and means adapted to be actuated by the engine shaft for controlling the opening movement of said 110 plate.

6. In an engine of the class described, a 115 housing, a shaft journaled therein, a rotor carried by said shaft and provided in its periphery with pockets each of which is provided with a radially disposed face at one end, there being an elongated combustion chamber formed in the annular wall of the engine housing, which combustion chamber is tangentially disposed with respect to the 120 periphery of the rotor, a spring-pressed plate adapted to close the forward end of said combustion chamber, means adapted to be actuated by the engine shaft for controlling the opening movement of said plate, and means actuated by the shaft of the engine for compressing combustible vapors in 125 said combustion chamber.

In testimony whereof I hereunto affix my signature this 3d day of September, 1919.

EDWARD L. HEITZ.
